BOX AND DISPENSER FOR GRANULAR MATERIALS

Vernon M. Campbell, Tipton, Ind.

Application February 2, 1956, Serial No. 563,002

4 Claims. (Cl. 222—455)

The usual cardboard boxes for the well-known granular soap powders are prone to discharge a great deal more of the powder than desired, unless great care is exercised.

The present invention is designed to overcome the above difficulty by providing a box having novel means which allows discharge of the contents only in measured quantity.

The box is provided with a measuring pocket which receives some of the box contents when the box is tilted, and is provided also with another pocket which receives the measured quantity when the box is again righted; and the material is discharged from the latter pocket when the box is again tilted. Thus, when using a freshly opened box, tilting, righting and re-tilting of the box will cause discharge of a measured quantity. After the first use of the box in this manner, it is only necessary to tilt it, as the prior tilting to effect discharge has caused refilling of the measuring pocket and this pocket has dumped into the other compartment upon righting of the box.

Another object of the invention is to provide a removable stop normally fitting into the second pocket and preventing any accidental reception of box contents therein during shipping and handling.

A further object is to provide the box with a novel hinged portion to cover the outlet of the dispensing means prior to first use thereof and after each subsequent use.

A still further object is to provide a simple and inexpensive dispenser construction which may be formed from two cardboard blanks.

With the above and other objects in view that will become apparent as the nature of the invention is better understood, the same consists in the novel form, combination and arrangement of parts hereinafter more fully described, shown in the accompanying drawings and particularly claimed.

In the drawings:

Fig. 1 is a perspective view of a box embodying the invention;

Fig. 2 is a vertical sectional view partly in section;

Fig. 3 is a similar view but showing the box tilted to fill the measuring pocket;

Fig. 4 is a similar view but showing the box righted and the measured quantity of material in the second pocket in readiness for discharge when the box is again tilted;

Fig. 5 is a plan view of the blank from which to form the major portion of the dispenser;

Fig. 6 is a plan view of the blank from which to form the top and a wall section of the dispenser;

Fig. 7 is an edge view of the top in folded position;

Fig. 8 is a plan view of the blank from which to form the removable stop;

Fig. 9 is an edge view of the stop; and

Figs. 10, 11 and 12 are side elevations showing various steps in forming the dispenser from the blanks.

The drawings illustrate a preferred construction which will be rather specifically described but it is to be understood that variations may be made within the scope of the invention as claimed.

2

A measuring and dispensing casing 15 is glued or otherwise secured in an upper corner of the box 16, and the latter is provided with a hinged corner portion 17 which may be swung open when dispensing is to be accomplished, but otherwise remains closed.

The casing 15 has parallel vertically elongated side walls 18 which lie against the box side walls 19. A top 20 and bottom 21 are secured to the side walls 18, the inner end of said top being glued or otherwise secured to the top 22 of the box 16. An inner vertical wall 23 is secured to the side walls 18, extends upwardly from the bottom 21 and terminates a short distance below the top 20, leaving an opening 24. One outer wall section 25 rises from the bottom 21 and inclines outwardly therefrom, said outer wall section 25 being secured to the side walls 18 and terminating below the top 20. A second front wall section 26 is connected with the side walls 18 and the top 20 and declines from the latter toward the inner wall 23, an opening 27 being left between said wall section 26 and said inner wall 23.

The side walls 18 project downwardly below the bottom 21 and their lower edges 28 are declined to one edge wall 29 of the box 16. An additional outer wall section 30 extends downwardly from the upper end of the wall section 25 and is secured against the box edge wall 29. This wall section 30 is secured to the side walls 18 and extends to the lower ends of the declined edges 28 thereof. An inclined wall 31 is connected with the lower end of the wall section 30, inclines along the edges 28 substantially to the bottom 21 and has a flange 32 glued or otherwise secured to the inner wall 23, said wall 31 being secured to the side walls 18.

The elements 20, 26 and 18 cooperate in forming a measuring pocket P to receive material from the box 16 when the latter is tilted. When the box is more or less full, tilting to the position of Fig. 3, for example, will suffice.

The elements 23, 21, 25 and 18 cooperate in forming a second pocket P' which receives the measured material from the pocket P when the box is righted (see Fig. 4). When the box is again tilted, the material will discharge from the pocket P' for use. During this tilting, pocket P refills and when the box 16 is again righted this pocket again empties into pocket P'. Thus, when the box is to be next used, only tilting thereof will be required to discharge the measured quantity of material. The same is true for all succeeding uses, and when the supply is about exhausted, necessitating greater tilting of the box to almost inverted position, the contents will slide down the wall 31 instead of being trapped.

A stop 33 is normally disposed in the lower pocket P' (Fig. 2) to prevent any of the box contents from reaching said pocket during shipment and handling. This stop 33 is formed from cardboard folded into substantially U-shape and having its ends connected by a pull strap 34. This strap preferably displays the word "Pull," indicating that the stop must be removed when the box is opened.

In Fig. 5, a cardboard blank is shown from which most elements of the dispensing casing 15 are formed. This blank has successive portions 23a, 21a, 25a, 30a, 31a and 32a to form the inner wall 23, bottom 21, outer wall sections 25 and 30, wall 31 and flange 32, respectively. The portions 21a and 25a have tabs 35 on their ends to be glued or cemented to the casing side walls 18 above described.

Lateral wings 18a are formed on the longitudinal edges of the blank portions 23a, and other wings 18b are formed on the corresponding edges of the portion 30a. These wings 18a and 18b jointly form the casing side walls 18 and impart a two-ply construction to the greater part of the same. The wings 18b have oblique ends to form the inclined lower ends of the side walls 18 and said oblique ends have flanges 28a to be glued or cemented against the

inclined wall 31. The wings 18a and 18b have acute angular notches 18c which locate the wall section 26 during construction of the casing 15.

The blank of Fig. 6 is used to form the casing top 20 and the outer wall section 26 and accordingly has the portions 20a and 26a. Flanges 36 and 37 are formed on this blank to be glued or cemented to the casing side walls. Fig. 7 shows the blank, flanges and tabs bent into proper relation in readiness for assembly.

A comparison of Figs. 10, 11 and 12 will reveal the manner in which the blanks of Figs. 5 and 6 are bent and assembled to form the casing 15. In Figs. 11 and 12, quantities of glue or the like are indicated at 38. The wings 18a and 18b are also glued or cemented together.

Fig. 8 discloses a blank 33a from which to form the stop 33 and its pull strap 34. The blank 33a is elongated and rectangular to be folded into U-shape, and one end of said blank has a relatively long and narrow extension 34a. When the blank is folded into U-shape (Fig. 9) part of the extension 34a is glued or cemented to one arm of the U, the remainder of said extension then forming the pull strap 34.

From the foregoing, it will be seen that novel and advantageous provision has been made for attaining the desired ends. Attention is again invited, however, to the possibility of making variations without departing from the spirit and scope of the invention as claimed.

I claim:

1. In a measuring and dispensing device for granular material, a box for the material, a vertically elongated casing secured in an upper corner of said box, said casing comprising parallel side walls, a top and a bottom secured to said side walls, an inner wall extending upwardly from said bottom and secured to said side walls, said inner wall terminating a short distance below said top, one outer wall section rising from said bottom and secured to said side walls, said one outer wall section terminating below said top, and a second outer wall section secured to said side walls and top and spaced above said one outer wall section, said second outer wall section declining toward said inner casing wall and terminating in spaced relation therewith; said top, said second outer wall section and portions of said side walls cooperating in forming an upper

pocket to receive material from the aforesaid box when the latter is tilted; said bottom, said inner wall, said one outer wall section and portions of said side walls cooperating in forming a lower pocket to receive the material from said upper pocket when the box is righted, permitting discharge of this material when the box is again tilted, an edge wall, said box having an opening which exposes the space between said outer wall sections to permit discharge of the material.

2. A structure as specified in claim 1; said side walls projecting below said bottom, a third outer wall section projecting downwardly from the upper edge of said one outer wall section and secured to the downwardly projecting portions of said side walls, said third outer wall section being secured against said edge wall of the box, and an additional wall under said bottom and secured to said side walls, said additional wall being inclined from the lower end of said third outer wall section to the lower end of said inner wall.

3. A structure as specified in claim 1, in which said top and said second outer wall section are formed from a one-piece blank, all other elements of said casing being formed from another one-piece blank.

4. A structure as specified in claim 1; said side walls projecting below said bottom, a third outer wall section projecting downwardly from the upper edge of said one outer wall section and secured to the downwardly projecting portions of said side walls, said third outer wall section being secured against said edge wall of the box, and an additional wall under said bottom and secured to said side walls, said additional wall being inclined from the lower end of said third outer wall section to the lower end of said inner wall, said top and said second outer wall section being formed from a one-piece blank, all other elements of said casing being formed from another one-piece blank.
